RECTIFIER PROTECTIVE CIRCUITS

Donald G. Little, Baltimore, and Charles K. Hooper, Linthicum Heights, Md., assignors to Westinghouse Electric Corporation, East Pittsburgh, Pa., a corporation of Pennsylvania

Application May 20, 1943, Serial No. 487,748

4 Claims. (Cl. 175—363)

1

Our invention relates to dry contact rectifiers, such as the well-known copper-oxide rectifiers, and in particular relates to arrangements for protecting such rectifiers from overheating.

Rectifiers of the dry-contact type generally pass a certain amount of current in the reverse direction, that is to say, in the direction in which they are nominally non-conductive. This reverse current is relatively small compared with the amount of current that they pass without overheating in their forward or nominally conductive direction. Investigation has shown that the reverse current which will pass with a given applied voltage in the reverse direction increases quite rapidly as temperature increases. This is true whether the rectifiers are of the copper-oxide type, the selenium-type, or of other types known to the art.

It is also well known that rectifiers of the contact type rapidly change their electrical characteristics with increase of temperature, and also that they are incapable of withstanding voltages greater than a certain critical amount impressed upon them in their non-conductive direction without suffering what may be termed a breakdown very similar to the dielectric breakdown of insulation. It is also found that the amount of this critical breakdown voltage decreases rather rapidly with increase of temperature. In any actual service, the voltage at which the rectifiers can operate under without suffering such a breakdown is an important factor in their first cost; in other words, the rectifiers have to be designed with a sufficient number of units in series so that the line voltage under which they are expected to operate will not cause their breakdown. The internal heat generated in the rectifiers in service naturally causes a rise in their temperature above that of their surroundings, and this fact has to be taken into consideration in designing a given rectifier, so that even with the temperature rise resulting from long continued operation at full load the impressed line voltage is less than the rectifier breakdown voltage. Furthermore, if the rectifiers overheat because of operating in excess of their rated load capacity, or because of some rise in the ambient temperature to abnormal values, the resulting lowering of their breakdown voltage may cause the normal operating voltage to cause their breakdown and consequent destruction.

Some means of giving an indication when the rectifier has exceeded the safe operating temperature for the particular line voltage being used is accordingly very desirable in practice. We have

2

discovered that the rapid increase of the reverse current through the rectifiers may be used as an expedient for giving warning when their temperature rises to a dangerous degree, and for operating relays or other devices for cutting them out of the electric circuit.

One object of our invention is accordingly to provide dry contact rectifiers with an efficient means for indicating their internal temperature.

Another object of our invention is to provide dry contact rectifiers with a device which shall indicate when their internal temperature rises above a safe value.

Another object of our invention is to provide copper-oxide rectifiers with an arrangement which shall indicate the magnitude of their resistance to current flowing in the reverse current direction.

Still another object of our invention is to provide copper-oxide rectifiers with means for removing them from an electrical circuit when their operating temperature has reached a predetermined value.

Other objects of our invention will become apparent from reading the following description when taken in connection with the accompanying drawing, in which:

Figure 1 is a graphical plot showing the relation between the current flowing through a contact rectifier in its non-conductive direction and the temperature of the rectifier; and

Fig. 2 is a schematic diagram of a rectifier circuit for making use of the principles of our invention.

Referring in detail to Fig. 1, temperature in degrees centigrade is indicated by the abscissae while the ordinates represent the reverse current, or the current which a certain impressed voltage will cause to flow through the rectifier in its nominally non-conductive direction. It will be evident from Fig. 1 that the reverse current rises slowly at first and at an increasingly rapid rate as the temperature rises. For example, the particular rectifier in question might be stable and able to operate safely at a certain line voltage at all temperatures below 80°. At temperatures well below 80°, the amount of reverse current would be very small, but in the neighborhood of 80°, it is increasing rapidly, and this abrupt increase of current may be used to indicate that the rectifier has attained a dangerous temperature, i. e., a temperature above 80° C. For example, a relay may be connected in circuit with the rectifier which shall remain inoperative as long as the

reverse current through the rectifier is less than that corresponding to 80° C. As soon as this temperature is exceeded, however, the relay may close a pair of contacts operating an alarm signal or even operating the tripping coil of a circuit interrupter which is in series with the rectifier.

Fig. 2 shows a circuit in accordance with our invention which is especially well adapted to utilize the rapid increase of reverse current to operate an indicating device when the critical temperature is reached. Fig. 2 shows one branch or limb of a rectifier which would conduct current in substantial amounts only in one direction. In short, Fig. 2 shows a half-wave rectifier. In actual practice, at least two such legs are usually connected by schemes well known in the rectifier art to conduct to a load both half-waves from the alternating-current source. For example, Grondahl Patent No. 1,640,335, assigned to the Union Switch & Signal Company, of Swissvale, Pennsylvania, illustrates a number of different connections for half-wave rectifiers to adapt them to conduct full-waves of direct current to a load when supplied by an alternating-current source.

The rectifier shown in Fig. 2 comprises a number of serially connected unit rectifiers which may, for example, comprise copper plates oxidized on one side, this side being thereafter coated with graphite and provided with a contact plate of lead or other impressionable material. Such rectifiers are fully described in the above-mentioned Grondahl patent. A plurality of such rectifiers, 1, 2, 3, 4, 5 and 6 may be connected in series with each other, the copper plate of one rectifier making contact with the contact plate of that adjacent to it. A lead wire 7, which may be connected to one side of an alternating-current source, is connected to, let us say, the copper plate of rectifier No. 1, and a second lead wire 8 adapted to be connected to the other side of the same source is connected to the contact plate of rectifier No. 6. The structure so far described constitutes a conventional half-wave rectifier, or one limb of a full-wave rectifier of the dry-contact type as known in the art.

Maintained in as good thermal contact as possible with, but separated from, the rectifier 6 by an insulating layer 9, is a rectifier 11, the rectifier 11 being reversely positioned in comparison with the rectifiers 1 to 6, so that its contact plate is most closely adjacent to the contact plate of the rectifier 6 and its copper plate most remote therefrom. A connection is made from the contact plate of the rectifier 5 to the copper plate of the rectifier 11. Between the contact plate of the rectifier 6 and the contact plate of the rectifier 11, i. e., connected so as to be shunted across the insulating layer 9, is the winding 12 of a relay. The relay 12 is so adjusted that its contacts 13, 14 are normally open, but are closed by the amount of current which flows through the rectifier 6 in the reverse direction when the normal line voltage is impressed between the lines 7, 8, and the temperature of the rectifier is at the critical value at which dangerous overheating begins. The contacts 13, 14 may be arranged to close the circuit of any desired indicator, such as a signal or bell, or alternatively, as shown in Fig. 2, close the circuit between a voltage source 15 and a tripping coil 16 of a circuit breaker 17 which is connected in series with line 8.

It will be noted that the winding 12 is connected in series with the rectifier 11 across the rectifier 6. The relative directions of the recti-

fiers 11 and 6 are such that when line current is in the nominally conductive direction through the rectifiers 1 to 6, practically no current flows through the winding 12 because to do so this current would have to flow in the nominally non-conductive direction in the rectifier 11. On the other hand, when reverse current tends to flow through the rectifiers 1 to 6, current can readily flow through the winding 12 because the rectifier 11 will then be transmitting this current in its conductive direction. Since the resistance to current flow in the last-mentioned direction which is interposed by the winding 12 and the rectifier 11 is arranged to be much smaller than the resistance to current flow in the reverse direction in the rectifier 6, practically all the reverse current which flows through the rectifiers 1, 2, 3, 4 and 5 is shunted away from rectifier 6 and flows through the winding 12. The effect of the above-mentioned connection of the rectifier 11 is accordingly to conduct the reverse current flowing through the rectifiers 1, 2, 3, 4 and 5 almost entirely through winding 12, but to prevent the flow through winding 12 of the load current which flows through the rectifiers 1, 2, 3, 4, 5 and 6 in their nominally conductive direction.

If the temperature of the rectifiers 1 to 6 rises beyond the safe critical value, the reverse current will be large enough to close the relay contacts 13, 14 and trip the circuit breaker 17 to cut the rectifier out of circuit.

We have shown the rectifier 6 as positioned at the end of the rectifier series, but the protective rectifier 11, which may be termed an ancillary rectifier, may be shunted across any one or more of the rectifiers of a series such as 1 to 6. The ancillary rectifier 11 has been described as a single unit, but for some purposes may comprise a number of units in series. The ancillary rectifier 11 and the rectifiers it shunts may be of the same type as the rectifiers 1 to 6, or may be of any different type having suitable rating to conduct the current and having other characteristics evident to those skilled in the art. While we have described our protective device as applied to a single stack or series of rectifier elements constituting a half-wave rectifier, the ancillary rectifier may be shunted across any one rectifier in a plurality of half-wave rectifiers arranged to produce full-wave rectification in any of the connections well known in the art for that purpose. In some cases, it may be desirable to provide an ancillary rectifier and current-responsive element for each limb or half-wave rectifier forming a component of such full-wave rectifier systems. While we have shown the half-wave rectifier stack as comprising six unit rectifiers in series, it will be evident to those skilled in the art that it may comprise any number from two up.

We have described a particular arrangement embodying the principles of our invention, but these principles are of broader application in ways which will be evident to those skilled in the art.

We claim as our invention:

1. In combination with a plurality of rectifier elements connected in series, a current path shunting a portion of said rectifier elements and comprising an ancillary rectifier of opposite polarity in series with a current-responsive device.
2. In combination with a plurality of rectifier elements connected in series, a current path shunting one or more but not all of said rectifier elements and comprising an ancillary rectifier in series with a device, said current path being re-

sponsive to the reverse current of said elements. 3. In combination with a plurality of rectifier elements connected in series, a current path shunting certain ones, but not all, of said rectifier elements and comprising an ancillary rectifier of reversed polarity in series with a current responsive device controlling a circuit interrupter governing current flow to said rectifier elements.

4. In combination with a plurality of rectifier elements connected in series, a current path shunting certain ones, but not all, of said rectifier elements and comprising an ancillary rectifier in series with a device, said current path being responsive to the reverse current of said elements, and said device controlling a circuit in- 15

interrupter governing current flow to said rectifier elements.
